CLAIM

The ornamental design for a display screen with a transitional graphical user interface for dental software, as shown and described.

DESCRIPTION

A portion of the disclosure of this patent document contains material to which a claim for copyright and trademark is made. The copyright and trademark owner has no objection to the reproduction of the patent document or the patent disclosure, as it appears in the U.S. Patent Office records, but reserves all other copyright and trademark rights whatsoever.

FIG. 1 is a front view of a first image of a display screen with transitional graphical user interface for dental software; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; FIG. 8 is a front view of an eighth image thereof; FIG. 9 is a front view of a ninth image thereof; FIG. 10 is a front view of a tenth image thereof; FIG. 11 is a front view of an eleventh image thereof; FIG. 12 is a front view of a twelfth image thereof; FIG. 13 is a front view of a thirteenth image thereof; FIG. 14 is a front view of a fourteenth image thereof; and, FIG. 15 is a front view of a fifteenth image thereof. The broken line depicts the display screen and forms no part of the claimed design.

The appearance of the transitional image sequentially transitions from the images shown in FIGS. 1 through 15. The process or period in which one image transitions to another image forms no part of the claimed design.

1 Claim, 15 Drawing Sheets
